CORNER RAIL FASTENER FOR BEDSTEADS

Filed July 5, 1922

By
Watson, Cott. Moore & Grindle,
Attorney

UNITED STATES PATENT OFFICE.

CLARENCE S. MOECKEL, OF ATLANTA, GEORGIA, ASSIGNOR TO SOUTHERN SPRING BED COMPANY, OF ATLANTA, GEORGIA, A CORPORATION OF GEORGIA.

CORNER-RAIL FASTENER FOR BEDSTEADS.

Application filed July 5, 1922. Serial No. 572,803.

To all whom it may concern:

Be it known that I, CLARENCE S. MOECKEL, a citizen of the United States, and a resident of Atlanta, Fulton County, State of Georgia, 5 have invented certain new and useful Improvements in Corner-Rail Fasteners for Bedsteads, of which the following is specification.

This invention relates to means for connecting together the ends of metal side and end rails of bedsteads and for connecting them to the bedposts at the corners and is adapted for use with bedsteads of various kinds, whether made of wood or metal. It is 10 designed and intended to produce and does in practice produce such a strong and rigid and properly distributed contact connection between the side rails and the corner brackets at the bedpost as to prevent all possibility of 15 longitudinal swaying of the head and foot of the bedstead in reference to the side rails and also such as will prevent any lateral distortion or disarrangement of the angular relations of the side and end rails when side 20 pressure is applied at one end of the bed to move it laterally. It also prevents rotary movement of the side rails when in position. It thus produces a very rigid bedstead structure where there is no lost motion to develop 25 wear and breakage but on the contrary where the parts are so constructed and arranged that any added weight on the bed automatically makes the connections tighter and more rigid. The structure furthermore 30 is very simple indeed and easily and cheaply made and may be applied to various kinds of bedsteads now in use. The novel features 35 will be more fully understood from the following description and claims taken with the 40 accompanying drawings.

In the drawings:

Figure 1 is a perspective view of a corner bracket embodying the present invention in place on the bedpost, the post and the side 45 rail being partly broken away;

Figure 2 is a side view looking from the left in Figure 1; and,

Figure 3 is a plan view looking down on the bracket and side rail.

In the embodiment of the invention shown in the drawing for the purpose of illustration, 10 represents the ordinary bedpost and 11 represents a bracket adapted to be secured to that or any other bedpost. This bracket 55 11 in the form shown is L-shaped in cross-

section having the vertically elongated flange portion 12 fitting against the side of the bedpost 10 and adapted to be secured thereto in any suitable way as by screws, rivets or bolts, passing through openings 13 and 14. Projecting forwardly from the portion 12 at one edge and in vertical position is the other flange 15 which is integral with it and which may be called the hook member. This flange is of substantially the same thickness as the flange 12 except that at the corner on the outer side where the flange 12 is joined it is of double thickness as at 16, forming a shoulder 17 on the outer side facing outward from the bedpost. The thin flange or hook member 15 has a slot 18 formed in it from its upper end a short distance outward from the shoulder 17 and forming the finger 19 at its outer edge having a rounded or inclined top portion 20 which is preferably below the upper edge of the hook member where it joins the flange 12 which is secured to the bedpost. The edge 21 of the finger 19 which faces the bedpost is at a slight incline from the upper end towards the lower end being the nearest 25 to the bedpost at the lower end.

The side rail 22 is L-shaped in section with the flange 23 horizontal in use and the flange 24 vertical. The flange 23 is preferably made of double thickness from the line 25 to the end and there is integral therewith in line with the flange 24, the upwardly projecting flange 26 which is of substantially the same width as the flange 24 and of the same thickness so that the result is that the end portion of this side rail 22 is T-shaped in section with the stem of the T in a horizontal position in use. The end of the flange 23 of the side rail 22 is cut away in next to the flange 24 at 27 on the arc of a circle and at the inner end of this arc there is a notch or groove 28 extending forwardly with one edge in the plane of the inner face of the flanges 24 and 26 and of such width as to fit the edge portion 29 of the hook member 15 at the rear of the slot 18. A slot 30 is also formed in the flange 23 of the side rail in the part of double thickness with one of its side walls in the plane of the inner surfaces of the flanges 24 and 26 and having a width great enough to receive and closely fit the finger 19. The length of this slot is somewhat greater than the breadth of the finger 19 longitudinally of the side rail. The ends of the vertical flanges 24 and 26 of the side 35 40 45 50 55 60 65 70 75 80 85 90 95 100 105 110

rail 22 terminate in the same vertical plane at right angles to the longitudinal lines of the side bar and the end 31 of the flange 23 terminates on a parallel plane beyond the ends of flanges 24 and 26 a distance equal to that which the face of the flange 12 is beyond the shoulder 17 longitudinal of the side bar. The end 33 of slot 30 against which the inclined face 21 of finger 19 bears is at 10 such distance from the end 31 and from the ends of the side flanges 24 and 26 that when it is in contact with finger 19, as shown in Figure 1, the end 31 will make end contact with the face of plate 12 and the edges of flanges 24 and 26 will be in contact with the shoulder 17.

It will be understood from what has been said as to the construction that the side rail when in the position shown in Figure 20 1 may be raised vertically so that it will move upwardly off finger 19 and its ends moving along shoulder 17 and plate 12 until the slot 30 is disengaged from the finger when the parts are completely separated. Since the finger 19 closely fits the 25 slot 30 and extends on both sides of flange 23 close against the faces of the flanges 24 and 26 it makes a strong connection for holding the side rail in proper upright position 30 and this is greatly increased by the end of the flanges 24 and 26 engaging the side of the flange 15 at the shoulder. The most important function and advantage of the construction however is that a mere down 35 movement of the side rail on the bracket by the action of the inclined edge of the finger 19 on the edge 33 of the slot in the side rail forces the side rail longitudinally, bringing the end 31 into tight contact with the face of the flange 12 and the end edges of the flanges 24 and 26 in tight contact 40 with the shoulder 17 throughout its length which is double that of the normal side rail L-shaped in section as shown. This 45 gives a very rigid construction which prevents all looseness and wear. It will be noted furthermore that the structural features are very simple, being largely L-shaped sections of metal.

50 Although one specific embodiment of the invention is shown for the purpose of illustration, it will be understood that it is not limited to that form beyond what is called for in the claims.

55 Having thus described the invention what is claimed as new and desired to be secured by Letters Patent is:

1. A device of the class described comprising in combination a bracket L-shaped in section one flange being adapted to be attached vertically to a bed post and the other having an extra thickness of metal 60 on the outer side from the angle a short

distance outwardly forming a vertical shoulder and a vertical slot outwardly beyond said shoulder forming a flat finger having its edge facing the other flange inclined towards it from the top, a side rail L-shaped in cross section having in its horizontal flange an end slot next to the vertical flange to receive the edge of the bracket flange beyond the vertical slot and a slot to receive and laterally fit the finger and bear against its inclined surface, the end of the slot in contact with the finger being at such distance from the ends of the flanges of said side rail that they will abut the shoulder and flange surface of the vertical bracket with a wedging action. 65 70 75

2. A device of the class described comprising in combination a bracket L-shaped in section one flange being adapted to be attached vertically to a bed post and the other having an extra thickness of metal on the outer side from the angle a short 80 distance outwardly forming a vertical shoulder and a vertical slot outwardly beyond said shoulder forming a flat finger having its edge facing the other flange inclined towards it from the top, a side rail L-shaped in cross section throughout most 85 of its length but having an end portion T-shaped in section with the stem of the T horizontal and extending beyond the ends of the T flanges with a groove next to those flanges at the end adapted to receive the edge of the bracket flange and a slot to receive its finger at such distance from the end that its downward movement on that 90 finger in close contact with the facing surfaces of the T flanges will by a wedging action force the ends of said flanges tightly against said shoulder and the end of the stem against the facing surface of the bracket flange. 95 100 105

3. A device of the class described comprising in combination a bracket adapted to be secured to a bed post, a thin vertical member projecting therefrom at one edge having a rib forming a vertically extending shoulder on the outer side near the base of said member and a vertically extending slot from the top forming a thin finger with its edge facing the bracket inclined towards it, a side rail having an end portion T shaped in cross section with the stem of the T horizontal and having an end 110 groove and aligned slot at the flanges to receive the edge of the bracket flange and finger with the ends of the T flanges in contact with said shoulder and the end of the stem flange in contact with the facing surface of the bracket. 115 120

In testimony whereof I hereunto affix my signature.

CLARENCE S. MOECKEL.
